CENTRIFUGAL LAUNDRY EXTRACTOR

Edmund J. Te Pas, Rocky River, Ohio, assignor
to The Apex Electrical Manufacturing Company, Cleveland, Ohio, a corporation of Ohio

Application February 1, 1933, Serial No. 654,628

9 Claims. (Cl. 210—71)

This invention relates to clothes drying machines of the centrifugal extractor type and it has for its object the provision of an improved form of extractor clutch and brake mechanism, 5 the provision of a simple and safe extractor control means, and the provision of an improved means for preventing the escape of grease into the extractor compartment or the leakage of water into the gear case and an improved clutch-10ing and braking mechanism.

With these and other objects in view, the invention consists in the novel construction, arrangement and combination of parts, hereinafter illustrated and described in some of its embodiments in the accompanying drawings, and particularly pointed out in the appended claims.

In the drawings Figure 1 is a side elevational view, partly in section, of an extractor mechanism illustrating one mode of practicing this invention.

Figure 2 is a plan elevational view of the top of the machine shown in Figure 1.

Figure 3 is an enlarged fragmentary view of certain details of the extractor control mechanism.

Figure 4 is an enlarged sectional view of the extractor drive gearing taken on line 4—4, Figure 1.

Figure 5 is a sectional view taken on line 5—5, 30 Figure 4.

Figure 6 is a sectional view taken on line 6—6, Figure 4, and

Figure 7 is an enlarged plan view of the brake shoe assembly.

The present invention may be used in connection with a combined washing and extracting machine of the type illustrated in Figure 3 of James B. Kirby, Patent 1,842,030, which was issued on January 19, 1932. Certain details of the washing mechanism of such a combined machine are not illustrated herein as they form no part of this invention.

In applying this invention to a combined washing and extracting machine of the type shown 45 in the patent above referred to, the extractor driving shaft 1 is connected through suitable gearing and mechanism to a rotatable extractor container 2 which is housed within the compartment 3 defined by a casing 4. The extractor container 50 2 may be provided with perforations 5 for the escape of fluid upon the rotation of the container. The extractor container has a work-receiving opening defined by the turned-over edge 6 at its upper end and is provided thereat with a cover 7 55 which in the present case serves as a guard for

the container 2 when it is in its closed position and as a clothes chute when it is shifted to its open position as is illustrated in dotted lines in Figure 2.

One of the important features of this invention 5 is that of utilizing the extractor cover 7 for controlling the operation of the extractor container in such a manner so as to prevent the starting of the extractor when the cover is in its open position.

The driving shaft 1 of the extractor container is connected by means of a universal joint to a stub shaft 8. This joint is provided with a dirt-excluding and grease-retaining cover 9. A channel or trough-shaped guard 10 is supported beneath the shaft 1. This guard extends a distance beyond the ends of the shaft 1 and serves to catch oil that might escape from the bearing beneath which it is positioned as well as providing a guard for the shaft.

The shaft 8 is journaled in suitable bearings 11 and 12 formed in the extractor gear case base 13. The shaft 8 is provided with a helical gear 14 which is rigidly fixed thereon at a point intermediate the ends of the shaft. An oil seal 15 prevents the escape of oil from about the bearing 12. The helical gear 14 engages a second helical gear 16, mounted for rotation about a vertical axis. A third helical gear 17, carried by the horizontal pump shaft 18 meshes with the last mentioned helical gear 16 for the purpose of driving the pump 19. A ball thrust bearing 20 is provided for the shaft 8.

An extractor basket supporting shaft 21 is mounted at its lower end in an anti-friction bearing 22. This bearing is fitted in a suitable opening 23 provided in the bottom half 13 of the extractor gear case. A closure cap 24 secures the bearing 22 in place in the gear case base. The extractor shaft 21 is provided with a threaded 35 lower end 25 for reception of a lock nut 26, by means of which the shaft 21 is secured to the cone or inner race 27 of the anti-friction bearing 22 whereby the shaft is held against axial movement.

The gear case for the extractor mechanism is 45 formed with lower and upper halves 13 and 28, respectively. The lower half of the gear case or base 13, is formed with bearings for the motor driven shaft 8 and supports for a pair of clutch or brake shafts 29 and 30. The cover or upper 50 half 28 of the extractor gear case is formed with a central opening 31, for reception of the extractor shaft upper bearing 32.

The extractor shaft bearing 32 is exteriorly threaded at 33 and is provided with an outwardly 55

extending flange 34, at its lower end. A nut 35, engaging the threaded part 33 of the bearing 32, is provided for securing the extractor gear case to the frame 36 of the machine and to the bottom 37 of the extractor tub 4. Suitable gaskets 38 are provided to prevent leakage of water about the central opening 39 of the extractor tub through which the bearing 32 projects.

The extractor shaft 21 is provided with a frusto-conical upper end 48, which is received in the frusto-conical socket 41 of the extractor basket base 42. By use of the form of coupling shown the extractor basket may be readily removed from its shaft 21. The coupling also constitutes a frictional driving connection between the basket and its shaft.

The extractor basket base 42 is in the form of a bell-shaped die casting. An inwardly tapering sheet metal drum 43 is secured to the base 42 by the rivets 44. The taper of the shaft end 40 is such that the weight of the basket is sufficient to provide for a good frictional driving connection at this point, while at the same time, permitting a slight amount of slippage in starting and stopping the rotation of the basket.

Perforations 5 are formed in the side walls of the basket to permit the expelling of water from the basket during its operation. The base portion of the extractor basket is provided with a plurality of holes 45, to permit the drainage of water from this portion of the basket. The upper end of the extractor basket carries an annular ring 46, which is provided to prevent clothes from dropping between the extractor basket and its tub 4. This ring may be of stamped metal construction and is pressed or spun into position on the top of the extractor basket.

A shaft seal is provided at the upper end of the shaft bearing to prevent the ingress of water into the extractor gear case and to prevent the escape of oil from such gear case into the extractor tub. This seal comprises a sealing ring 47 having a smoothly finished edge which contacts with the smoothly finished upper end 48 of the extractor shaft bearing 32. The sealing ring 47 is fixed to rotate with the extractor shaft by means of its contact with the yielding packing ring 48. The packing ring is forced against the shaft and the sealing ring 47 by means of a gland 50 which is pressed against the packing material by means of a spring 51 which abuts against the bottom of the extractor basket. The packing ring 49 is preferably made from an oil proof soft rubber and is sufficiently yielding to permit slight angular or wobbling movements of the sealing ring 47 which is rather loosely fitted on the shaft 21 to allow for such movements.

The helical gear 16 is fixedly secured to a clutch member 52, which is rotatably journaled on the extractor shaft 21. At its upper end the clutch member 52 is provided with a conical clutch face 53. The member 52 is held against axial movement by means of the shaft shoulder 54 and the collar 55.

Co-operating with the clutch member 52, which is fixedly connected to the spiral gear 16, there is provided a second clutch member 56, which has an inner conical clutch face 57, provided for cooperation with the clutch face 53 of the aforementioned member 52. The clutch member 56 is slotted at 58, for receiving the shaft key 59. In this manner the member 56 is mounted for rotation with the shaft and for axially slidabile movement thereon.

A spring 60 is compressed between the top of

the clutch member 56 and the washer 61, which is held in position on the shaft 21 by means of the pin 62. The outer face of the vertically slidabile clutch member 56 is formed with a frusto-conical brake face 63, which engages a pair of brake members or shoes 64 and 65 having brake faces 66 and 67 respectively of similar contour. The brake members 64 and 65 are provided with a pair of vertical fins 68, 69 and 70, 71 which are provided for reception of the cams 72 and 73 of the clutch or brake shafts 29 and 30. The brake members 64 and 65 rest on ledges 74 provided by the upper edge of the gear case base 13.

The brake shoes 64 and 65 are provided with oppositely facing pins 75 and 76 for supporting the compression springs 77, by means of which the brake shoes are urged away from the brake face 63 of the member 56. The springs 77 also serve to maintain the brake shoes in contact with the cams 72 and 73. Suitable set screws 78 and 79 are provided to secure the cams 72 and 73 to their respective shafts 29 and 30. The shafts 29 and 30 are connected to each other by means of the rod 80 which is pivotally secured to oppositely located cranks 81 and 82 carried by the shafts 29 and 30 so that upon the rotational movement of the shaft 29, the shaft 30 is moved an equal amount in an opposite direction.

The shaft 29 is provided at its outer end with a crank arm 83. Suitable oil seals (not shown) are fitted in the outer end of the bearing of the shafts 29 and 30 to prevent the escape of oil from the gear case at these points. The crank arm 83 is rigidly secured to the end of the shaft 29 and is held thereon by means of the nut 84. The crank arm 83 is engaged by the lower end of a rod 85, which is operated by means of the cams 86 and 86a carried by the extractor cover 7. Contact is maintained between the rod 85, the cam 86, and arm 83, by means of the tension spring 87, which is secured at its opposite ends to the crank 83 and to the washing machine base 88.

The cam 86 has a slot for receiving the pivoted cam 86a which has a handle 86b for effecting the stopping of the extractor when the cover is closed. The lower end of the rod 85 is drilled threaded for the reception of the bolt 88, by means of which its length can be readily adjusted. A lock nut 89 is provided for the bolt 88. The head of the bolt is received in a shallow cup 91, which is formed in the end of the crank arm 83. The washing machine top plate 92 has an apertured arm 93 integrally formed therewith for receiving and guiding the upper end of the rod 85. The lower end of the rod 85 is guided in a bracket 94 which is carried by the machine base 88.

During the operation of the washing machine motor, and with the parts in the position they occupy in Figures 1 and 5, the extractor basket will be at rest with the braking surfaces 63 and 66 and 67 in contact with each other. To start the rotation of the basket it is only necessary to close the lid 7, whereupon the movement of the cam 86 allows the rod 85 and the crank arm 83 to rise under influence of the spring 87. The movement of the crank arm 83 is transmitted to the shafts 29 and 30 which cause the cams 72 and 73 to move away from the brake shoes 64 and 65 allowing these members to separate and to move out of engagement with the brake face 63 of the member 56. Coincidentally with this operation, the spring 60 moves the clutch member 56 downwardly, bringing the frictional clutch

faces 53 and 57 into engagement with each other, whereupon the basket 2 is driven by the rotating member 52.

The disengaging of the clutch and the stopping 5 of the extractor is automatically accomplished by opening the lid 7 or by turning the cam 86^a by means of its handle 86^b. These operations move the aforesaid extractor control elements in a manner reverse to that just explained, to bring 10 the brake surfaces together and in this manner raise the member 56 to separate the clutch surfaces 53 and 57, whereupon the basket 2 is quickly brought to rest.

From the foregoing it is apparent that the 15 mechanism shown provides a simple and fool-proof extractor control, the manipulation and operation of which may be readily learned in a few moments. By reason of using the extractor lid as the operating member of the control 20 it is impossible to start the extractor without placing it in a safe operating condition with its lid closed and similarly when the lid is opened to permit access to the extractor basket this element is quickly brought to rest by the movement 25 of the lid.

Furthermore it is to be understood that the 30 particular forms of apparatus shown and described, and the particular procedure set forth are presented for purposes of explanation and that various modifications of said apparatus and procedure can be made without departing from this invention as described in the appended 35 claims.

Having thus described my invention what I claim is:

1. A centrifugal extractor comprising, a casing, a rotatable container having an opening in its upper end, a cover for the top of said container pivoted to said casing, power means for driving said container, clutch means for connecting and disconnecting said container to said power means, operative connections between said cover and said clutch means, and supplemental means independent of said cover for controlling the operation of said container.

2. A centrifugal extractor comprising, a casing, a rotatable container having an opening in its upper end, a cover for the top of said container pivoted to said casing, power means for driving said container, clutch means for connecting and disconnecting said container to said power means, control devices connected to said clutch means and operated by said cover for controlling the operation of said container, and additional means for operating said control devices independently of said cover.

3. A centrifugal extractor comprising, a casing, a rotatable container having an opening in its upper end, a cover for the top of said container pivoted to said casing, power means for driving said container, means for disconnecting the driving connection between said power means and container, brake means for stopping the rotation of said container after its driving connection with said power means has been disconnected, operative connections between said cover and said brake means, and supplemental means independent of said cover for controlling the operation of said brake means and the stoppage of said container.

70 4. A centrifugal extractor comprising, a casing,

a rotatable container having an opening in its upper end, a cover for the top of said container pivoted to said casing, power means for driving said container, means for disconnecting the driving connection between said power means and container, brake means for stopping the rotation of said container after its driving connection with said power means has been disconnected, control devices connected to said brake means and operated by said cover for controlling the operation of said brake means and the stoppage of said container, and additional means for operating said control devices independently of said cover.

5. A centrifugal extractor comprising, a casing, a rotatable container having an opening in its upper end, a cover for the top of said container pivoted to said casing, power means for driving said container, clutch and brake means for connecting and disconnecting said container to said power means and for stopping its rotation, operative connections between said cover and said clutch and brake means, and supplemental means independent of said cover for controlling the operation of said container.

6. A centrifugal extractor comprising, a casing, a rotatable container having an opening in its upper end, a cover for the top of said container pivoted to said casing, power means for driving said container, clutch and brake means for connecting and disconnecting said container to said power means and for stopping its rotation, operative connections between said cover and said clutch and brake means, and supplemental means independent of said cover and movable about the pivot axis thereof for controlling the operation of said container.

7. A centrifugal extractor comprising, a casing, a rotatable container having an opening in its upper end, a cover for the top of said container pivoted to said casing, power means for driving said container, clutch and brake means for connecting and disconnecting said container to said power means and for stopping its rotation, control devices connected to said clutch and brake means and operated by said cover for controlling the operation of said container, and additional means for operating said control devices independently of said cover.

8. A centrifugal extractor comprising, a casing, a rotatable container having an opening in its upper end, power means for driving said container, clutch and brake means for connecting and disconnecting said container to said power means and for stopping its rotation, and control means for said clutch and brake means including independently operable actuating members each of which may be separately used to start and stop said extractor.

9. A centrifugal extractor comprising, a casing, a rotatable container having an opening in its upper end, power means for driving said container, clutch and brake means for connecting and disconnecting said container to said power means and for stopping its rotation, and control means for said clutch and brake means including a pair of independently operable actuating members located adjacent to the top of the extractor either one of which may be used to start and stop said extractor.
